Patented Nov. 14, 1967

209,196

WHEEL

John A. Main, East Lansing, and Dann T. Deaver, Mount Clemens, Mich., assignors to Motor Wheel Corporation, Lansing, Mich., a corporation of Ohio

Filed Jan. 5, 1966, Ser. No. 466

Term of patent 14 years

(Cl. D14—30)

FIG. 3

FIG. 4

FIG. 6

FIG. 7

FIG. 1 is a front elevational view of a wheel showing one embodiment of our new design.

FIG. 2 is a sectional view taken on line 2-2 of FIG. 1.

FIG. 3 is a fragmentary elevational view of a portion of the wheel of FIG. 1 but greatly enlarged thereover.

FIG. 4 is a sectional view taken on the line 4-4 of FIG. 3.

FIG. 5 is a front elevational view of a wheel showing a second embodiment of our new design.

FIG. 6 is a fragmentary elevational view of a portion of the wheel shown in FIG. 5 but greatly enlarged thereover.

FIG. 7 is a sectional view taken on the line 7-7 of FIG. 6.

The characteristic feature of our design resides in the provision of plastic inserts arranged in a circle on the disc of the wheel in alternating relationship with vent holes in the disc and of contrasting color and configuration with the disc and adapted to stand out from the face of the disc and be thrown into sharp relief by their contrasting colors and configuration, as shown.

We claim:

The ornamental design for a wheel, substantially as shown and described.
